UNITED STATES PATENT OFFICE

GEORGE W. BOWEN, OF AUBURN, NEW YORK

METHOD FOR THE ASSEMBLY AND INSTALLATION OF TURNTABLES

Application filed September 4, 1928. Serial No. 303,847.

This invention relates to a new and improved method for the assembly and installation of turn tables.

In assembling and installing turn tables it is very essential that the turn table be level and that the track which supports it also be level. When the turn table proper is assembled without reference to the track and the track is laid without reference to the turn table it is extremely difficult to obtain a satisfactory installation and if the turn table and the track are not properly installed the operation of the turn table will be difficult and the wear on the different parts will be excessive.

The main object of my invention is to devise a method whereby a turn table may be assembled and installed in conjunction with the track upon which it is supported so that when the installation has been made the turn table and the track must be properly installed in relation to each other and in relation to the surface of the roadway or floor in which it is installed.

Other objects and advantages relate to the means employed and to the progressive steps used in accomplishing the desired results all as will more fully appear from the following description taken in conjunction with the accompanying drawings, in which:

Figure 1 is a top plan view of a turn table partially assembled and prepared for the pouring of a concrete base.

Figure 2 is a top plan view of a completed installation.

Figure 3 is a section on line 3—3 of Figure 1.

Figure 4 is a section on line 4—4 of Figure 1.

Figure 5 is a section on line 5—5 of Figure 4.

Figure 6 is a section on line 6—6 of Figure 4.

Figure 7 is a section on line 7—7 of Figure 2.

Figure 8 is a section on line 8—8 of Figure 7.

Figure 9 is a section on line 9—9 of Figure 2.

For the purpose of explaining my new and

improved method for the assembly and installation of a turn table I have here shown a turn table of the type disclosed in my copending application filed December 10, 1927, Serial No. 239,135 which consists of a center bottom plate —1— and a center top plate —2— between which are secured a plurality, in this case shown as sixteen, of radially extending stringers —3— by means of bolts —4—. A top bearing plate —5— is secured to the under surface of plate —1— by means of bolts —6— which extend upwardly through plate —1—, stringers —3— and top plate —2—. A bottom bearing plate —7— is positioned in a support —8— preferably of concrete. A ball —9— is interposed between bearing plates —5— and —7—. A roller —9'— is secured to the under surface of each of the stringers —3— at the outer end thereof by means of bolts —10—. Adjacent stringers —3— are secured together by means of planks —11— for the purpose of securing stringers —3— in spaced relation and to provide a platform for the turn table. A circular track —12— is positioned beneath the under surface of stringers —3— and in registration with the under surfaces of rollers —9'—. I also provide on the end of each stringer —3— an oil tube —13— in communication with the bearing of rollers —9'— so that the same may be supplied with lubricant from time to time as desired. I also provide through one of the stringers —3— a vertically extending oil tube —13— through which lubricant may be supplied to the track —12—. Another oil tube —15— extends through top plate —2—, bottom plate —1— and bearing plate —5— to permit the supplying of lubricant to ball —9—.

For the purpose of retaining the turn table in a fixed position when desired I provide on the upper surface thereof two opposed latches —16— and —17— which may alternately be placed in registration with a keeper —18— which is positioned adjacent the upper surface of the turn table.

My improved method of assembling and installing a turn table consists of providing a pit as —19— circular in shape and of a diameter greater than the diameter of the turn

table and of a depth so that when the supporting base —20—, preferably of concrete, has been placed in position the upper surface of the turn table will be flush with the surrounding ground or floor in which the turn table is installed.

At the central point of the pit —19— I place the support —8— and the bearing —7—. The top plate —2—, bottom plate —1—, bearing plate —5—, stringers —3— and rollers —9— are then assembled in the manner above described.

For the purpose of insuring that the concrete base and side wall which I provide for pit —19— shall be in the proper position in relation to the turn table I provide a concrete form —21— of a size and shape to register with the ends of stringers —3—. Form —21— is provided with spaced brackets —22— at its upper edge which register with the top surfaces of stringers —3— and which are secured thereto by means of bolts —23—. Supporting bracket —24— has its upper end secured to bolt —23— and its lower end secured to form —21— by means of pin —25—. I preferably make form —21— in sections so that it may be disassembled to permit of easy transportation. For the purpose of permitting such assembly and disassembly of form —21— I provide on the ends of the sections of form —21— a dove-tail member —26— which is inserted into a corresponding groove in bracket —22— and which may be removed therefrom as desired.

35. The dove-tail members —26— are so positioned on form —21— that when they are inserted into brackets —22—, brackets —22— being secured to stringers —3—, stringers —3— will be held in the proper spaced relation with reference to each other.

40. Track —12— is preferably made in sections held together by opposed track angles —27— and —28— which are secured thereto by rivets —29—. Track angles —27— and —28— in addition to securing the adjacent ends of track —12— together function as anchors in the concrete base upon which the track is eventually supported.

45. I next secure track —12— to rollers —9— by means of clamps —30— which have inwardly extending jaws —31— in registration with the flanges —32— of rollers —9— and which have another set of jaws —33— between which track —12— is secured. Clamps —30— are held in position by means of bolts —34—.

50. I next place upper bearing —5— in registration with lower bearing —7— and with ball —9— therebetween.

55. 60. Stringers —3— are then supported by means of posts —35— and wedges —36—. By means of wedges —36— the outer ends of stringers —3— are then raised or lowered as may be required until the upper surfaces of stringers —3— are level.

Cement is then poured onto the bottom of pit —19— and between the outer surface of form —21— and the inner surface of pit —19—. The pouring of the cement is continued until it is of a sufficient thickness to cover the lower edges of track —12— and the outwardly flaring portions of track angles —27— and —28—.

65. It is preferable to so form the bottom surface of pit —19— that pit —19— will be deeper on one side than on the other and when this is done, as perhaps may best be seen from Figures 7 and 8, one edge of track —12— will be approximately flush with supporting base —20— as shown at —a— on Figure 7 while the other side of track —12— will be supported upon a built up portion —37— of supporting base —20—. Raised portion —37— gradually diminishes in height until it merges with supporting base —20—. The purpose of this construction is to permit the drainage of water from the higher portion of supporting base —20— to the lower portion of supporting base —20— and in order to permit the removal of such moisture I provide in raised portion —37— an opening —38— in registration with a drain pipe —39— which leads to a sewer or cesspool, not shown.

70. 75. When the concrete is being poured I place adjacent the outer end of one of the stringers —3— a form of wood (not shown) so that when form —21— is removed and the form of wood also removed there will be a recess —40— in the outer wall of the pit lining which recess will permit the insertion of lubricant into oil tubes —13— as the same are brought into registration with it. A cover —41— is normally in position over recess —40—.

80. 85. 90. When the cement has become set I remove clamps —30— from track —12— and rollers —9— and I also remove form —21— from the ends of the stringers —3— by removing bolts —23— which bolts —23— are replaced by bolts —10— to secure rollers —9— in position. I also remove wedges —36—. Planks —11— are then placed in position on stringers —3— and secured thereon by screws or other convenient means.

95. 100. 105. The method of assembly and installation of a turn table as just described insures that the rollers on the turn table will be in proper relation to the track and it also insures that the turn table as a whole will be in proper relation to the pit in which it is positioned.

110. 115. 120. It will be understood that my method and installation of a turn table may be applied to any turn table which is provided with rollers and a supporting track therefor without departing from the spirit of my invention for altho I have shown and described my method of assembly and installation as applied to a particular type of turn table as an exemplification of my method I do not de-

sire to restrict myself to the particular type of turn table shown for my method may be applied to different types of turn tables and it may also be modified to a considerable extent without departing from the invention as disclosed in the appended claims.

What I claim is:

1. The method of assembling and installing a turn table comprising assembling the center bearing of the turn table with the radially extending stringers, assembling the outside rollers on the stringers, spacing the stringers, securing the track to the underside of the rollers and flowing concrete beneath the turn table to grip and secure in position the track, and releasing the track from the rollers.
  2. The method of assembling and installing a turn table comprising assembling the center bearing thereof with the radially extending stringers, attaching a concrete form to the outer end of the stringers, attaching rollers to the underside of the outer end of the stringers, securing a track to the rollers, flowing concrete around the form and beneath the turn table to a depth sufficient to grip the track and secure the same in position, and then releasing the track from the rollers and the concrete form from the stringers.
  3. The method of assembling and installing a turn table comprising assembling the center bearing of the turn table with the radially extending stringers, placing the stringers with their upper surfaces in a level position, assembling the outside rollers on the stringers, spacing the stringers, securing the track to the underside of the rollers and flowing concrete beneath the turn table to grip and secure in position the track, and releasing the track from the rollers.
  4. The method of assembling and installing a turn table comprising assembling the center bearing thereof with the radially extending stringers, placing the stringers with their upper surfaces in a level position, attaching a concrete form to the outer end of the stringers, attaching rollers to the underside of the outer ends of the stringers, securing a track to the rollers, flowing concrete around the form and beneath the turn table to a depth sufficient to grip the track and secure the same in position, and then releasing the track from the rollers and the concrete form from the stringers.
- 55 In witness whereof I have hereunto set my hand this 23d day of August, 1928.

GEORGE W. BOWEN.
